(57) **CLAIM**

The ornamental design for an electric scooter, as shown and described.

DESCRIPTION

FIG. 1 is a front and top perspective view of an electric scooter, showing my new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of the handlebar in FIG. 1;

FIG. 10 is a partial enlarged view of the kickstand area in FIG. 2; and,

FIG. 11 is a partial enlarged view of the front suspension area in FIG. 5.

The dash-dot broken lines represent the boundaries of the enlarged partial views of FIGS. 9-11 and form no part of the claimed design.
